THOMAS F. MULLIGAN, OF FORT WAYNE, INDIANA, ASSIGNOR TO S. F. BOWSER & COMPANY, INCORPORATED, OF FORT WAYNE, INDIANA, A CORPORATION OF INDIANA.

REMOTE-CONTROL PUMPING SYSTEM.

1,175,170.

Specification of Letters Patent. Patented Mar. 14, 1916.

Application filed October 23, 1911. Serial No. 656,113.

To all whom it may concern:

Be it known that I, THOMAS F. MULLIGAN, a citizen of the United States, residing at Fort Wayne, in the county of Allen and 5 State of Indiana, have invented certain new and useful Improvements in Remote-Control Pumping Systems, of which the following is a specification.

This invention relates to a pumping system in which a valve to control the supply pipe is situated at a place remote from the pump which supplies fluid to the pipe, and the present exemplification of the invention is described as employing an electric motor 15 to operate the pump.

The principal object of this invention is to provide means whereby the motor and pump may be stopped while the valve is still open, and to shut off the pump before the 20 valve is completely closed, thus avoiding "ramming" in the discharge pipe.

A further object is to provide an improved, simple, effective and efficient system of the class described for controlling a 25 supply of fluid at the point where the fluid supply is discharged.

For the attainment of these ends and the accomplishment of other new and useful objects as will appear, this invention consists 30 in the features of novelty in the construction, combination and arrangement of the several parts generally shown in the accompanying drawing and described in the specification, but more fully pointed out in the 35 appended claims.

In the drawing, Figure 1 illustrates a system embodying the principles of my invention, and Fig. 2 is a detailed view partly in section of a motor controlling switch and 40 the means for operating the same.

It has become the practice to employ motor driven pumps for supplying fluid at a distant point, and if the pump is not stopped before the valve at the distance point is 45 closed, there will be a ramming in the pipe which may cause leakage in the pipe or which may throw such a load upon the motor that it will be stopped and serious damage be done to the motor armature. This 50 invention had for its object to provide means for operating the motor whereby it will be stopped before the valve is closed, and will be started after the valve is opened.

Referring more particularly to the drawing, the motor M is directly connected to a

pump P, and extending from the pump, is a discharge line 10. In this discharge line 10 there is located a valve V which may be of any suitable or desired construction, but preferably is of the class in which the valve stem 11 is rotated to produce the opening and closing of the valve 12. Suitably positioned upon the valve and in the present exemplification of the invention adjacent the top of the valve stem, is a stationary and adjustable switch holding device 13, which is adapted to provide a support for the switch S. This switch S may be of any desired or suitable construction, but is preferably of a type in which electrical contact is made and broken between two terminals by means of push buttons. In the present exemplification of the invention, a switch constructed as shown in Fig. 2, will answer the purpose. In this switch a contact bar 14 is pivotally mounted and adapted to make and break connection between terminals 15 and 16, which in turn are connected to the conductors 17 and 18 respectively. Push buttons 19 and 20 are adapted to engage the bar 14, and to cause it to make and break connections with the terminals accordingly, as one or the other of them is pushed. These push buttons 19 and 20 are disposed adjacent to the valve stem 11, and a segment 21 is pivotally mounted upon the supporting device 13 so that it will engage both of the push buttons 19 and 20. This segment 21 is provided with a groove or hollowed out portion 22 in which a pin 23 attached to the hand wheel or other suitable rotating part of the valve stem, is adapted to engage. It will be seen that as the pin engages the groove, the push buttons will be moved in accordance with the movement of the pin, 90 resulting in the opening or closing of a circuit between the terminals 15 and 16. The wires or conductors 17 and 18 are connected one to the negative source of current supply, and the other through a magnet relay 100 24 to the positive source of supply.

The magnet relay 24 controls a starting device which may be represented as shown in Fig. 1. A pivoted lever 25 is provided with a bar 26 at one end which is attracted by the magnet. The other end of the bar is adapted to pass over the contacts 27 between which is the starting resistance 28. A conductor 29 forms a connection between the last contact and one terminal of the motor, 110

and the other terminal of the motor is connected to the negative main by the conductor 30. The lever 25 is connected to the positive main by the conductor 18.

5 To operate the motor and the pump, the valve is first turned until the switch is closed, which closes a circuit through the magnet relay, thereby causing the magnet to be energized and the bar 26 to be drawn 10 up. The arm of the lever 25 is moved over the contacts from the stop position shown in dotted outline in Fig. 1, which completes an energizing circuit to the motor. As soon as the switch is opened, by the operation of 15 the valve hand wheel, the energizing current for the magnet relay is broken and the weight of the bar 26 is sufficient to return the lever 25 to the dotted stop position.

In the present exemplification of the invention, the switch S is so positioned, that the movement of the hand-wheel to close the valve, will effect the breaking of the circuit connection in the switch as soon as the closing movement is started, or at least before the valve is entirely closed, and in the other direction or rotation of the hand-wheel, the switch is operated to close the circuit connections, at or about the time when the valve is completely open. From this it 50 will be evident that the motor will not receive current at any time when the valve is closed, and consequently, there can be no action of the pump in the discharge pipe 10, because the pump is connected to the motor and the motor is stopped before the valve is closed, and is started after the valve is opened.

It is also evident that by having the support 13 adjustable above the valve, the points of opening and closing the switch may be varied as desired.

When the current required to operate the motor is small in amount, the starting device may be dispensed with and the motor circuit from the mains may be closed and opened by the switch.

I desire not to be limited to any particular construction of valves, switches, pumps or motors, as it is evident that these devices may be of any well known construction.

What I claim is:

1. A remote control pumping system comprising an electric motor, a pump connected thereto, a discharge line from the pump, an electric switch connected in series with the motor, and a valve with a rotary stem for opening and closing the discharge line with a projection to operate the switch to close the motor circuit just before the valve is entirely open and to open the motor circuit 60 when the valve starts to close, thereby insuring that the valve is open whenever the motor and pump are in operation.

2. A remote control pumping system comprising an electric motor, a pump connected thereto, a discharge line from the pump, a positively operated electric switch for controlling the motor, a valve with a rotary stem for opening and closing the discharge line, and a stop in connection with the rotary stem to positively close the switch just before the valve is entirely open and to positively open the switch at the initial closing movement of the valve.

In testimony whereof I have signed my 75 name to this specification, in the presence of two subscribing witnesses, on this 19th day of October A. D. 1911.

THOMAS F. MULLIGAN.
